Primary Examiner — Rhea Shields(74) *Attorney, Agent, or Firm* — Sterne, Kessler, Goldstein & Fox PLLC.(57) **CLAIM**

The ornamental design for a package with accessory, as shown and described.

DESCRIPTION

FIG. 1 is a top front perspective view of a package with accessory showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The shade lines in the figures show contour and not surface ornamentation.
